YARN FEEDING MECHANISM FOR TWISTING AND DOUBLING MACHINES

Carl C. Sorensen, Charlotte, N. C.

Application August 26, 1936, Serial No. 97,984

4 Claims. (Cl. 117—21)

This invention relates to yarn feeding means for twisting and doubling machines in which an individual unit is associated with each spindle and whereby two strands can be fed to each 5 spindle at different rates of travel whereby the desired effect can be produced in the yarn.

It is therefore an object of the invention to produce mechanism associated with a twisting and doubling machine in which two yarns, either 10 single or combined, are fed to a spindle at different rates and whereby a yarn of less tensile strength such as fine count cotton can be twisted or doubled with a stronger yarn such as rayon, or acetate or combination thereof and thereby 15 eliminate many of the parting of the ends which heretofore have occurred in such circumstances. This mechanism also lessens the stretch in the 20 yarn which is fed at the faster rate; it increases the breaking strength of combination yarns, especially acetate and crepe combinations irrespective 25 of the number of ends used. By using a fast feed roll and a slow feed roll to wrap one yarn around another a knitting yarn can be produced in which one strand will have more slippage over 30 the other so as to obtain different effects in the fabric, such as cotton and acetate yarns and also combinations of rayon, acetate and silk yarns.

It is still another object of the invention to provide a pair of feed rolls for a doubling and 35 twisting machine driven at different rates of speed. This result is obtained by using the conventional feed rolls which are now driven at the same rate of speed and around which a yarn is wound, by providing means whereby the two feed rolls are driven at different rates of speed to feed two 40 different yarns to the spindle.

It is a further object of the invention to replace the individual feed units on present twisters with a pair of individual rollers for each spindle 45 which have means for driving the rollers at different speeds so that two yarns can be fed at the same time to a spindle. In this case one yarn is wrapped around one feed roll several times to prevent slippage, while the other yarn is also wrapped around the other feed roll in a like manner.

The purpose of the invention is to allow a 50 faster delivery of one yarn when two or more ends are being twisted together. For example, if an end of acetate and an end of rayon is to be 55 twisted into one thread and a certain effect like having the acetate thrown to the front, the rayon would be wrapped around the slow feed roll and the acetate around the fast feed roll.

The speed with which the one yarn is to be

thrown faster into the two ply can be controlled by interchanging the fast feed roll gear. Namely, if the yarn is to be fed real fast a small number of tooth gear would have to be inserted and if to be fed only slightly faster a larger tooth gear 5 would be inserted.

With this attachment if a yarn is rather difficult to run without taking out too much stretch it can be placed over the fast feed roll. Running 10 in this manner it also avoids breaking so many filaments on rayon or acetate particularly and makes a cleaner thread.

In many combinations, such as alpaca's and 15 types of twist such as this in which rayon crepe and regular acetate is twisted together and sometimes this again plied, it is necessary to get the best effect to feed one yarn in faster. The percentage of increase depends on the deniers and the number of turns needed for the effect in the fabric needed. With this attachment one 20 yarn can be fed 5% faster and up to the required amount to give the best balanced and weaving or processing yarn.

This same fast feeding of one yarn can also 25 be made for hosiery yarns using various types of rayon, cotton, silk or mixed yarns, as before enumerated. In other words if one yarn is desired to be wrapped around the other or others so that more of the exterior yarn will show on the face of the fabric, the yarn desired to show 30 would be wrapped around the fast feed roll. The amount will be determined by the effect desired. For example, if a fabric for hosiery was needed in which the silk showed on the face more pronounced than the present method of twisting, 35 the silk would be fed in faster and at the rate determined by effect wanted. As before stated, this would be accomplished by changing the fast feed roll gear.

Some of the objects of the invention having 40 been stated, other objects will appear as the description proceeds when taken in connection with the accompanying drawings, in which:—

Figure 1 is an elevation of one end of a doubling 45 and twisting machine showing my invention applied thereto;

Figure 2 is a vertical sectional view taken along the line 2—2 in Figure 1;

Figure 3 is a vertical sectional view taken along 50 line 3—3 in Figure 1;

Figure 4 is an enlarged detail sectional view taken along line 4—4 in Figure 1 showing the invention;

Figure 5 is a sectional view looking at the 55

opposite side of Figure 4, with the housing cover removed;

Figure 6 is a sectional plan view taken along line 6—6 in Figure 4;

5 Figure 7 is an enlarged sectional plan view taken along line 7—7 in Figure 4;

Figure 8 is an enlarged view of a pair of strands twisted in accordance with the invention.

Referring more specifically to the drawings, 10 the numeral 10 denotes an end frame of a doubling and twisting machine which has secured to the bottom portion thereof longitudinally disposed struts 11 and 12. A longitudinally disposed strut 13 is also secured to the upper portion. 15 These struts have their other end secured to another end frame not shown, similar to end frame 10 to form a complete framework for holding the apparatus. Secured to end frame 10 is a bracket 14 upon which is mounted a motor 15, said motor being connected by means of a suitable coupling 16 to shaft 17. The shaft 17 has a sprocket 18 fixedly secured thereon which sprocket drives a sprocket chain 19. Sprocket chain 19 is also mounted on another sprocket 20 which, in turn, is fixedly secured upon shaft 21. 25

The shaft 17 has a gear 25 keyed thereon which is adapted to constantly rotate pinions 26 and 27 which pinions are fixedly secured upon shafts 28 and 29 respectively. The shafts 28 30 and 29 extend longitudinally of the machine and have located thereon at spaced intervals suitable gears 30, which gears mesh with gears 31 mounted on spindle shafts 32. A spool 33 is placed upon the upper portion of spindle shaft 35 32 for receiving the yarn after it has been twisted.

A suitable ring rail 34 encircles the spool 33 and is adapted to be oscillated up and down to traverse the length of the spool to cause the yarn which has been twisted to be wrapped there-around. The yarn which is wrapped around the spool 33 is twisted immediately before being wrapped thereon and the twisted strand will be designated by the reference character 36. This strand comprises a pair of strands such as 37 40 and 38 said strands being drawn downwardly from spools or cones 39 and 40 respectively, through a suitable tension device 41 and thence downwardly through the feeding device 42 which is the present invention.

50 The parts designated by the reference characters 10 to 41 inclusive are conventional but it is deemed necessary to show this much of the old structure to more clearly disclose the present invention.

55 The feeding device 42 is fixedly secured to vertically disposed shaft 45, which shaft has its upper end slidably mounted in bracket 46. The lower end of shaft 45 is pinned to a horizontally disposed link 50 which link has its other end 60 pinned to the upper end of vertically disposed shaft 51. This shaft 51 extends downwardly and has its lower end slidably mounted in longitudinally disposed strut 11 or 12 and its upper end is slidably mounted in housings 52, which 65 housings normally contain an oil or a suitable lubricant for the gears therein. The rod 51 has secured to the lowermost end a foot pedal or projection 53 which is adapted to be engaged by the operator's foot when it is desired to throw 70 the feeding apparatus in gear. A compression spring 54 is confined around the rod 52 by means of a collar 55 and also by means of struts 11 or 12 to normally force the parts into a disengaged position; however, after it has been once placed 75 into an engaged position, by exerting pressure

upon foot pedal 53, the parts will remain in engaged position until certain mechanisms are operated to throw the parts out of gear. These parts are conventional, and a description of the same is therefore not deemed necessary.

5 The shaft 21 also has fixedly secured thereon a pinion 60, which pinion meshes with an idler pinion 61. The pinion 61 also meshes with another pinion 62 which is fixedly secured on one end of a short shaft 63, said shaft 63 being 10 mounted in bracket 64. The other end of shaft 63 has secured thereon a gear 65 which meshes with pinion 66 mounted upon longitudinally disposed shaft 67. (Figs. 1, 2 and 3.)

By means of idler gears 68 and 69 another 15 pinion 70 is driven by pinion 66 and this pinion 70 is fixedly secured upon longitudinally disposed shaft 71 which is similar in all respects to shaft 67 and performs the same function.

These shafts 67 and 71 have fixedly secured 20 thereto at spaced intervals suitable gears 75, which are constantly rotated and are adapted to mesh with gears 76 of the feeding attachment 42. The gear 76 is pinned on one end of a shaft 77 which shaft is rotatably mounted in a suitable bushing 78. This bushing is secured in hub portion 79 of housing 80. Secured to the other end of shaft 77 by any suitable means such as a pressed fit is a feed roller 82 around which strand 37 is wound. The strand 37 is also wound 30 around a pin 83 which extends outwardly in parallel relation to the shaft 77. By wrapping strand 37 around both of the members 82 and 83 the proper amount of tension is produced in the strand and it enables one to vary the speed 35 at which the strand is fed.

40 Loosely mounted around the hub of pinion 76 is a plate 86, which plate has rotatably mounted therein as at 87 an idler pinion 88. This idler pinion is adapted to also mesh with another pinion 89 which is secured on shaft 90. The pinion 89 is removably secured to the shaft 90 since it has a slot 91 in the hub thereof which is penetrated by a suitable pin 92, said pin also being fixedly secured in shaft 90. (Fig. 7) A 45 washer 94 and a screw 95 normally hold the pinion 89 on the shaft 90 in such a manner that the pin 92 will penetrate the slot 91 in the hub of pinion 89. Shaft 90 is rotatably mounted in a suitable bushing 97 which bushing is also secured in hub portion 98 of housing 80. Fixedly 50 secured on the other end of shaft 90 by any suitable means such as a pressed fit is another feed roller 99 around which the strand 38 is wound. The strand 38 is also wound around a suitable pin separator 100 which extends outwardly in parallel relation to the shaft 90. The number of turns which are made around the roll 99 and separator 100 will determine the amount of tension placed upon the strand 38 and will also play an important part in the speed of the strand 38 as it is being fed downwardly from the spool 40 to be twisted with strand 37. 55

60 In Figures 4 and 5, it will be noted that pinion 89 is smaller than pinion 76, hence the pinion 89 will be driven at a higher rate of speed than the pinion 76. Likewise, the roller 99 will be driven at a higher rate of rotation than the roller 82; consequently, the strand 38 will be fed downwardly faster than the strand 37. The strand 38 70 is usually made of some suitable material such as acetate, cotton, rayon, silk or any combination thereof and is fed so fast relative to strand 37 that the strand 38 is not stretched as much as strand 37, thereby throwing the greater tension 75.

upon the strand 37. The strand 37 usually has greater strength than strand 38; consequently, strand 37 is fed around the slow feed roll 82, whereas, the strand 38 usually has less strength hence, it is fed from around the fast feed roll 99 so that the strand 38 will be virtually wrapped around strand 37. By providing a construction of this type it is possible to have a combination strand, which, when the tension is applied to the finished strand, the elastic strand 38 will break approximately at the same time that the less elastic strand 37 will break, hence a maximum tensile strength from the combined strands of twisted yarn is obtained. Heretofore, these strands have been fed through and doubled at the same speed on silk twisters or doublers; consequently, due to the elastic limit of both of the strands 37 and 38 being different, one of the strands would be broken before the maximum strength of the other strand has been reached, therefore, the maximum tensile strength of the combined strand would not be obtained.

In order to vary the speed of the feed roll 99 the pinion 89 has been made removable as heretofore stated. If it is desired to increase the speed of shaft 90 and the feed roll 99, the pinion 89 will be removed and a smaller pinion will be placed thereon. Since the idler pinion 88 is rotatably secured to plate 86, this pinion can be 30 radially adjusted about the shaft 77 so that it will mesh with both pinions 76 and 89 regardless of what size pinion 89 might be. When it has been adjusted to the proper position, a set screw 102 is screwed home into housing 89 to fixedly 35 hold the plate 86 in its proper position. This set screw normally penetrates a radially disposed slot 103 cut in this plate. A cover 104 is secured to the housing 89 by any suitable means such as screw 105 to normally close one side of the housing.

In the drawings and specification there has been set forth a preferred embodiment of the invention, and although specific terms are employed, they are used in a generic and descriptive

sense only, and not for purposes of limitation, the scope of the invention being set forth in the appended claims.

I claim:

1. In a twisting machine having a plurality of spindles, a feeding unit for each spindle comprising a pair of feed rolls, common means for driving all of the rolls of said units, one of said rolls having a geared connection with said common driving means, a geared connection between one 10 roller and the other roller, said geared connection having an interchangeable gear therein so that the rate of rotation of one roll can be varied with relation to the other roll.

2. In a twisting machine having a plurality of 15 spindles, a pair of feed rolls for each spindle around each of which a strand of yarn may be wound to feed the strands to the spindle, means for driving the rolls at different rates of speed to feed the yarn on one roller to the spindle at 20 a faster rate than the yarn on the other roller is fed to the spindle, and means for changing the relative rate of rotation of the two rolls.

3. In a twisting machine having a plurality of 25 spindles onto which the twisted strand is wound, an individual feed unit for each spindle, each individual unit comprising a plurality of feed rolls and each roll being adapted to have wound there-around a strand for feeding the same to the spindle, and means for driving the feed rolls in 30 a unit at different rates of speed to thereby feed the strands to the spindles at different rates of travel.

4. In a twisting machine having a plurality of 35 spindles onto which the twisted strand is wound, an individual feed unit for each spindle, each individual unit comprising a plurality of feed rolls and each roll being adapted to have wound there-around a strand for feeding the same to the spindle, and positively driven means for driving 40 the feed rolls in a unit at different rates of speed to thereby feed the strands to the spindles at different rates of travel.

CARL C. SORENSEN.
